UNITED STATES PATENT OFFICE.

DAVID B. HYDE, OF SPRINGFIELD, OHIO.

GRINDING AND POLISHING WHEEL.

SPECIFICATION forming part of Letters Patent No. 688,942, dated October 8, 1901.

Application filed April 4, 1901. Serial No. 54,257. (No model.)

To all whom it may concern:

Be it known that I, DAVID B. HYDE, a citizen of the United States, residing at Springfield, in the county of Clark and State of Ohio, have invented certain new and useful Improvements in Grinding and Polishing Wheels, of which the following is a specification, reference being had therein to the accompanying drawings.

10 This invention relates to grinding and polishing-wheels and is in the nature of an improvement upon the construction set forth in the application filed by me June 11, 1900, Serial No. 19,800.

15 The object of the present invention is to provide a firm and uniform gripping of the wheel by the clamping-plates; and to these ends the invention consists in certain novel features, which I will now proceed to describe and will then particularly point out the claim.

20 In the accompanying drawings, Figure 1 is a central sectional view of a structure embodying my invention in one form. Fig. 2 is a view of the inner face of one of the clamping-plates, and Fig. 3 is a detail view of a modified form of the teeth or serrations.

25 In my prior application above referred to I have described a grinding and polishing wheel comprising a wheel proper having its sides converging toward its outer periphery, the same being held in position on the mandrel by a pair of clamping-plates having their inner faces concave to engage with said wheel on opposite sides thereof and provided with teeth or serrations formed on said plates adjacent to said wheel. In the construction therein set forth these teeth or serrations are shown as being uniformly and equidistantly 30 distributed over the entire inner surface of each clamping-plate. I have found in practice that it is advantageous to arrange the teeth or serrations in groups separated by intervening spaces, there resulting from this 35 arrangement two advantages—first, that the number of teeth being reduced the amount of pressure on each individual tooth is correspondingly increased, and the bite or hold thereof is consequently improved, and, second, that the intervening spaces not provided with teeth serve to give a greater measure of

accommodation for inequalities on the clamping-surfaces of the grinding-wheel.

In carrying out my invention I have shown a grinding-wheel 1, which may be of any suitable material and which is so constructed that its sides converge toward its outer periphery. This wheel is provided with the usual opening 2 to receive the mandrel or spindle 3, said opening being provided with a filling 4 of lead or the like in the usual manner, and the spindle being provided with a fixed collar 5, movable collar 6, and clamping-nut 7 or any other suitable means for tightening up the clamping-plates. The clamping-plates 65 are indicated at 8 and are concave on their inner faces to fit the tapering wheel. The inner face of each disk is provided with annular groups 9, composed of teeth or serrations 10, the spaces 11 being not provided 70 with teeth. These annular groups may be of any suitable number, and the number of teeth or serrations in each group may be varied. It will be noted that the omission of teeth at the blank spaces so reduces the number of teeth or serrations on each disk that when a given pressure is applied to the clamping-plates the pressure on each tooth is correspondingly increased over what the pressure would be if the entire surface of the 80 clamping-plate were covered with teeth. The effective holding power of each tooth is thereby correspondingly increased. It will also be observed that the blank spaces thus left provide a correspondingly large area, which 85 will accommodate inequalities of the clamping-surfaces of the wheel without contacting with said inequalities, and thereby producing unequal strains when the wheel is clamped. The wheel is thus more firmly and evenly 90 held and the device as a whole is rendered more effective.

In Fig. 1 of the drawings I have shown teeth the sides of which are inclined at equal angles to the surface of the wheel with which 95 they contact. This construction may, however, be modified, and in Fig. 3 I have shown a construction in which teeth are employed whereof those faces which are nearest the spindle are substantially perpendicular to 100 the surface of the wheel. The form of the teeth may be otherwise varied, and the de-

tails of construction hereinbefore set forth may be modified, and I therefore do not wish to be understood as limiting myself to the precise construction hereinbefore described, 5 and shown in the accompanying drawings.

Having thus fully described my invention, what I claim as new, and desire to secure by Letters Patent, is—

In a grinding and polishing wheel, the combination, with a wheel proper having its sides converging toward its outer periphery, of a 10 pair of clamping-plates having their inner faces concave for engaging with said wheel

proper on opposite sides thereof, said inner faces being provided with annular groups of 15 teeth or serrations formed on said clamping-plates adjacent to said wheel proper and with intermediate blank or toothless spaces, substantially as described.

In testimony whereof I affix my signature 20 in presence of two witnesses.

DAVID B. HYDE.
